UNITED STATES PATENT OFFICE.

JOSEPH O. RICHARD, OF SYRACUSE, NEW YORK.

WINDOW-FIXTURE.

1,046,646.

Specification of Letters Patent. Patented Dec. 10, 1912.

Application filed May 11, 1912. Serial No. 696,594.

To all whom it may concern:

Be it known that I, JOSEPH O. RICHARD, of Syracuse, in the county of Onondaga, in the State of New York, have invented new and useful Improvements in Window-Fixtures, of which the following, taken in connection with the accompanying drawings, is a full, clear, and exact description.

This invention relates to window fixtures and pertains more particularly to means for supporting curtains and shades.

The object of my invention is to provide a combination fixture upon which may be supported a curtain and a shade, the curtain fixture being extensible outwardly and the shade fixture longitudinally.

A further object is to provide a fixture which shall be foldable or separable into two parts for shipping in a small space, and means for holding the same in operable position when in use.

Figure 1 is a perspective view of the fixture. Fig. 2 is a cross section on line 1—1, Fig. 1. Fig. 3 is a cross section on line 2—2, Fig. 1. Fig. 4 is a cross section on line 3—3, Fig. 1. Fig. 5 is a cross section on line 4—4, Fig. 1.

—1 is a base plate having the lugs —2— projecting therefrom. These lugs are provided with apertures —3— for the reception of projections —4— upon the arms —5— and —6—. The body piece of the curtain fixture is a substantially flat piece of metal having the cylindrical apertures —7— and —8— longitudinally therethrough for the reception of the bolts —9— and —10—. The cylindrical aperture —8— has a portion thereof cut away to allow the insertion of a nut —11— upon bolt —10— by means of which the curtain holder is extended longitudinally and the movement thereof is positively controlled. The bolts —9— and —10— terminate in a single rod —12—, bent to form a hook for the reception of a curtain pole. The base plate —1— is also provided with a channel —13— formed by the two parallel plates —14— and —15— immovably attached to the base and having lateral extensions —16— and —17— thereon. In this channel is a plate —18— having upwardly extending arms —19— and —20—, the arm —19— being of greater length than —20— and having a slot in its outer

end adapted to receive the end of a shade roller. The arm —20— has an aperture 55 therethrough into which projects the bolt —21— to which it is immovably attached. The base —1— is also provided with two upwardly extending lugs —22— and —23— having alining apertures —24— and 60 —25— therethrough for the passage of bolt —21—. Between these lugs —22— and —23— and on the thread bolt —21— is placed a nut —26—. It is readily apparent that by turning the nut, the part —20— will 65 be either forced away or drawn toward lug —23— carrying along with it plate —18— and arm —19—, thus extending or shortening the distance between the respective shade receiving portions —19— on either 70 side of the window. One of the lugs —2— is provided with a second aperture —27— adapted to receive a second projection —28— on the arm —5— for holding the curtain plate —29— in upright position 75 when in use.

What I claim is:

1. A window fixture comprising a base, an upright pivotally mounted thereon, substantially parallel conduits extending longitudinally in said upright and a curtain retaining member having substantially parallel extending arms adapted to enter the conduits in the upright and means for adjusting the curtain retaining member longitudinally with respect to the upright. 85

2. A window fixture comprising an upright pivotally mounted upon a base, a conduit extending longitudinally in said upright, a threaded rod provided with means for retaining a curtain pole slidably mounted in said conduit, said upright provided with a lateral opening extending through the conduit and a nut seated in said opening and operably positioned on the threaded rod. 95

3. A window fixture comprising an upright mounted upon a base, a conduit extending longitudinally in said upright, said upright provided with a lateral opening extending through the conduit, a threaded rod provided with means for retaining a curtain pole mounted in said opening, and a nut seated in said opening and operably positioned on the threaded rod. 100

4. A window fixture comprising a base,

an upright mounted thereon, a conduit extending longitudinally in said upright, said upright provided with a lateral opening extending through the cylindrical opening, a
5 threaded rod mounted in the conduit opening, a nut seated in the lateral opening and operably positioned on the threaded rod.

In witness whereof I have hereunto set my hand on this 9th day of May 1912.

JOSEPH O. RICHARD.
